UNITED STATES PATENT OFFICE.

GEORGE D. BARNARD, OF ST. LOUIS, MISSOURI.

BOOK.

SPECIFICATION forming part of Letters Patent No. 390,197, dated October 2, 1888.

Application filed August 20, 1887. Serial No. 247,464. (No model.)

To all whom it may concern:

Be it known that I, GEORGE D. BARNARD, of St. Louis, Missouri, have made a new and useful Improvement in Books, of which the following is a full, clear, and exact description.

The improvement relates to that class of books in which the signatures are attached to guards or strips, which in turn are attached to whatever constitutes the book-back.

It consists in the special manner of constructing the guard or strip and attaching it to the signature and back, substantially as is hereinafter described and claimed, and illustrated in the annexed drawings, making part of this specification, in which—

Figure 1 is a view in perspective showing a signature attached to a guard. Fig. 2 is an end elevation of the same. Fig. 3 is an end elevation showing the assembled guards attached to the back-straps, the straps being passed through perforations in the guards. Fig. 4 is another end elevation showing the back-straps applied against the inner edges of the guards, and Fig. 5 is a rear elevation showing several guards with a strap passed through them and the relation of the stitching to the strap.

The same letters of reference denote the same parts.

A represents an ordinary signature.

B represents a guard. It is a substantially solid piece of substantially the shape shown, and the signature is attached thereto as follows: A thread, C, is passed through the middle of the opened signature and then into and through the guard from its outer, b, to its inner edge, b', then carried along the inner edge, b', substantially as shown in Figs. 1 and

5, then returned through the guard and signature, and so on forward and backward throughout nearly the length of the guard and signature. In this manner the guard and signature become strongly attached together, and the stitching does not appear upon the sides 40 of the guard, nor does any fastening need to be carried around the guard, and thus the guard is not unduly thickened.

The guards may be attached to whatever constitutes the book-back in any of the usual 50 methods. The back-straps D D may by the usual means be secured directly to the inner edge of the guards, as shown in Fig. 4, or they may be passed through the guards, near the inner edge thereof, as shown in Figs. 3 and 5, to which end the guards are suitably perforated 55 to receive the straps.

The subject-matter described and claimed in the pending applications of mine for Letters Patent for an improvement in books, 60 refiled August 12, 1887, and March 2, 1888, respectively, and numbered serially 246,763 and 265,973, respectively, I do not in this application desire to claim.

I claim—

The combination, in a book, of the signatures, the guards, and the back-straps, said signatures and guards being united by means of stitching carried through the middle of the signature and through the guard from its 70 outer to its inner edge, and said guards and back-straps being united, substantially as described.

Witness my hand.

GEORGE D. BARNARD.
